UNITED STATES PATENT OFFICE

2,293,383

POULTRY COOP

William H. Cramer, Garnett, Kans.

Application April 11, 1940, Serial No. 329,166

1 Claim. (Cl. 217—62)

This invention relates to poultry coops, one of the objects being to provide a coop which can be handled readily, and is formed of readily assembled units each of which can be readily made and possesses more than ordinary strength.

A further object is to provide the coop with a closure having improved means for holding it detachably in closed position, said closure being removable readily.

A still further object is to provide a coop the sides and ends of which are formed with open spaces through which the poultry cannot escape but through which containers holding water can be inserted easily.

With the foregoing and other objects in view which will appear as the description proceeds, the invention consists of certain novel details of construction and combination of parts herein-after more fully described and pointed out in the claim, it being understood that changes may be made in the construction and arrangement of parts without departing from the spirit of the invention as claimed.

In the accompanying drawings the preferred form of the invention has been shown.

In said drawings

Figure 1 is a top plan view of a poultry crate embodying the present improvements.

Figure 2 is a side elevation thereof, a portion being broken away.

Figure 3 is an end elevation, parts being in section.

Figure 4 is an enlarged section on line 4—4, Figure 1.

Figure 5 is an enlarged section on line 5—5, Figure 1.

Figure 6 is an enlarged section on line 6—6, Figure 4.

Figure 7 is an enlarged section on line 7—7, Figure 2.

Referring to the figures by characters of reference, 1 and 2 designate the end and side strips respectively of the bottom portion of the coop, these strips being joined at their ends to the lower ends of corner posts 3 while bottom boards 4 are attached to the strips and constitute a floor for the coop.

Intermediate posts 5 are attached to and extend upwardly from the respective end strips 1 and serve to connect said end strips to intermediate rails 6 and top rails 7 these rails also being attached to the corner posts 3.

Interposed between the rails 6 and 7 is a strip of wire fabric made up of vertical wires 8 having parallel upper and lower wires 9 and 10 joined

thereto by welding, with solder, or in any other suitable manner. The lower ends of the wires 8 are extended through bores 11 in the intermediate rails 6 while the upper ends of wires 8 are extended through bores 12 in the top rails 7. It is intended to insert the ends of the wires into the bores in the respective rails 6 and 7 and when these rails are brought into contact with the wires 9 and 10 which thus limit the movement of the rails toward each other, the ends of the wires 8 are clinched as shown at 13, thereby holding the rails securely assembled with the fabric and with each other. In the operation of assembling the parts the spaced wires 9 and 10 constitute gauges for insuring proper positioning of the rails 6 and 7 relative to each other.

The coop includes two end units each of which is made up of the strip 1, rails 6 and 7, corner post 3, intermediate posts 5, and the connecting wires. In addition thereto there are provided two side units.

As shown particularly in Figure 2, each side unit comprises end posts 14 which are attached to and extend upwardly from strip 2 and are adapted, when the coop is assembled, to abut against the posts 3 of the end units. These end posts 14 connect strip 2 to a top rail 15 and an intermediate rail 16 and these rails are joined by a strip of wire fabric including stiff vertical wires 17 the ends of which are extended through bores 18 in the rails 15 and 16. Spaced parallel wires 19 are welded or otherwise fixedly joined to the wires 17 and are adapted to extend along the rails 15 and 16. These wires 19 constitute abutments for the rails when the ends of the wires 17 are inserted into the bores 18. When the rails are brought firmly against the wires 19, the ends of the wires 17 are clinched onto the rails as shown at 20, thereby holding the parts properly assembled.

A partition is preferably placed in the coop at the center thereof so as to extend transversely. This partition includes a frame 21 having a wire fabric 22 fastened thereto.

The top of the coop is formed of two panels extending longitudinally thereof and spaced apart. Each panel includes longitudinal strips 23 connected by a strip of wire fabric 24. These panels are so proportioned that the ends of strips 23 can be nailed down onto the upper ends of the posts 3 and 5.

The space provided between the panels and extending lengthwise of the coop constitutes the opening through which the poultry can be inserted into or removed from the coop. This

space normally is closed by a strip 25 preferably of wood which extends throughout the length of the crate and is adapted to be removably mounted on the top of the frame 21 and also on the top rails 7 of the end units. For the purpose of holding the closure strip in place, stiff wires are bent substantially in a U-shape to form parallel legs 26 which are inserted downwardly through bores formed in the rails 6 and 7. The uppermost portion of the wire provides a flat loop 27, the wire being offset at the base of the loop as shown at 28, so as to rest on the rail 7 when the lower ends of the legs of the wire are clinched as shown at 29. Each loop 27 is wider than the strip 25 and provides a clearance sufficiently large to permit convenient insertion of the strip into the loop. That portion of the closure strip 25 located above the partition frame 21 has a notch 30 in one side thereof and a retaining wire 31 in the form of a broad flat staple is clinched into the top of the frame 21 as shown in Figure 4 so as to provide a guide and retainer for the middle portion of the closure strip 25.

In the top portion of the frame 21 adjacent to the loop 31 is clinched a prong 32 constituting one end of a spring wire. This prong merges downwardly into a coil 33 from which extends a spring arm 34 terminating in a loop 35. This loop, which embraces the guide 31, is adapted to bear laterally against the closure strip 25 so as to hold the notched portion 30 of said strip in engagement with one side of the retaining or guide loop 31 as shown particularly in Figures 1 and 4. Obviously with the closure strip thus pressed laterally into engagement with the intermediate guide loop 31, said strip is prevented from being withdrawn longitudinally from position between the top panels. It can only be removed by first pressing it laterally against the action of the spring arm 34 so as to withdraw the notched portion 30 from engagement with the guide. With the strip thus shifted, it can be pulled or pushed longitudinally from the coop.

In practice the end units and the side units are separately constructed as are the top panels and the partition frame. If preferred the strips 1 and 2 can be made a part of the bottom unit,

these strips being fastened together at their ends and having the floor boards 4 attached to them. If the coop is made in this way, the parts of the different units are assembled after which the corner posts 3 and 14 are placed together and the ends of the strips 1 and 2 are secured thereto while the ends of the rails 6 and 16 are joined together and the ends of the rails 7 and 15 are also fastened together. The partition 10 is secured in position by nailing and the top panels are then fastened on the side and end units, thus completing the assembly.

By providing spaces between the lower or intermediate rails of the end and side units and the bottom strips 1 and 2, the hands of a person carrying the coop can be inserted readily under the rails 6 or 16 so that the coop thus can be easily handled. Furthermore the spaces provided between the bottom strips and the intermediate rails permit the insertion of containers holding water.

What is claimed is:

In a poultry coop end panels each including upper and lower rails and a transverse partition frame, said coop having a longitudinal top opening extending across the partition frame and upper rails, retaining wires extending transversely within the opening above the upper rails and the partition, parallel legs formed with each wire, the legs of one wire being clinched within the partition and the legs of the other wires being clinched within the lower end rails, all of the legs being extended through and offset over the upper rails, an elongated flat closure 30 above the top level of the top rails and removably seated in the opening and under the retaining wires between the offset legs of said wires, there being a notch in one side edge of the closure, yielding means connected to the partition and protected by the crate, said means being located at all times in the crate and positioned for engaging the other side edge of the closure for holding the notched portion 35 astride one leg of one of the retaining wires, and a loop at one end of said yielding means extending around and guided by one of the retaining wires.

WILLIAM H. CRAMER.
